UNITED STATES PATENT OFFICE.

OTTO F. FOGELSTRAND, OF KENSINGTON, CONNECTICUT, ASSIGNOR TO
HART MANUFACTURING COMPANY, OF SAME PLACE.

DESIGN FOR A DOOR-BUTTON.

Specification forming part of Design No. 5,992, dated July 16, 1872.

Specification describing a Design for a Door-Button, invented by OTTO F. FOGELSTRAND, of Kensington, in the county of Hartford and State of Connecticut.

The nature of my design is fully represented in the accompanying engraving, to which reference is made.

A represents the base, to which the button B is secured; and C represents the striker. The contour of the parts A C are composed of straight and curved lines, joined as shown in the drawing, and both are bordered by a plain ledge. In the space inclosed by said ledge is ornamental work in relief, and the re-

maining space is covered by fine check-work. The button B has a ledge around its base—a central hub—the sides of which are fluted, and each arm of said button has a fluted rib extending centrally its whole length, and upon the front face of each arm at the sides of the ribs are oblique bars, as shown.

I claim as my invention—

The design for a door-button, as shown in the accompanying drawing.

OTTO F. FOGELSTRAND.
